UNITED STATES PATENT OFFICE.

ROBERT P. DUNN, OF ST. LOUIS, MISSOURI.

BEARING.

Application filed April 6, 1923. Serial No. 330,365.

This invention relates generally to bearings and particularly to a bearing intended for use on clothes washing and similar machines.

As is well known many machines for washing clothes have been produced each of which comprises a rotatable or oscillatory drum within a stationary housing. In the operation of clothes washing machines of the type mentioned, water is introduced into the outer stationary housing, which water passes through apertures in the shell of the rotatable inner drum. The clothes to be washed are placed in the inner drum and said drum is rotated or oscillated thereby violently agitating the clothes and water within said drum whereby said clothes are washed.

Prior to this invention much inconvenience and annoyance have been occasioned in the use of washing machines of the type described by water from within the machine finding its way into the bearings which support the inner drum, and by oil or grease from the bearing finding its way into the water within said machine. It is apparent that in the event that either of the above suggested possibilities occur much damage would be done, as if the water got into the bearings the oil or grease therein would be washed away leaving the working parts un-oiled, whereby the machine would not operate as it should and said parts would rust, or if the oil from the bearings worked its way into the machine, said oil would soil the clothes in the inner drum.

The bearing disclosed in the present application is so constructed and arranged that it is practically impossible for the water from the machine to get into the bearing, or for oil or grease from the bearing to get into the inner drum whereby the annoyance mentioned above is eliminated.

Fig. I is a vertical section of a fragment of a clothes washing machine provided with my improved bearing.

Fig. II is a side elevation of the machine illustrated in Fig. I, a portion of one of the legs of said machine being broken away.

Fig. III is a section on line III-III of Fig. I.

In the drawing, A designates a clothes washing machine comprising a stationary outer housing B provided with legs B', and a rotatable or oscillatory drum C within said outer housing B. Arranged on each end

wall of the inner drum C of the washing machine A is a trunnion 1 which extends outwardly from said end wall and is provided with a recess 2 extending inwardly into said trunnion. The trunnions 1 are preferably bolted to the end walls of the inner drum C and each of said trunnions extended through an opening in the adjacent end wall of the outer housing B.

Arranged on the outside face of each end wall of the outer housing B is a spider 3 comprising a plurality of legs which are secured to the adjacent end wall by means of bolts or other fastening devices. Each of the spiders 3, as will be seen by referring to Fig. I of the drawing, is provided with a trunnion 4 which extends into the recess formed in the associated trunnion 1 on the inner drum C. The trunnions 4 are of less diameter than the diameter of the recesses 2 so that spaces are provided between the peripheral faces of said trunnions and the annular walls of said recesses.

Located within the spaces between the peripheral faces of each trunnion 4 and the annular walls of the associated recesses 2 are roller bearings 5, the rollers of said bearings being mounted in suitable cages and said rollers being adapted to contact with sleeves formed of hard material, which sleeves are mounted on the outside face of the trunnion 4 and on the wall of the recess 2, respectively, said sleeves being intended to reduce the wear to which the faces of the trunnions 4 and the walls of the recesses 2 would be otherwise subjected. To retain each of the roller bearings 5 in place, I employ an externally threaded collar 6 which is adapted to screw into the end of the recess 2 and bears against an end of said roller bearing 5 whereby the opposite end of said roller bearing is forced against an annular shoulder 7 within said recess 2. After the collar 6 has been screwed into place and the roller bearing 5 is locked between said collar 6 and the shoulder 7, I form an internally threaded hole, half of which is in the trunnion 1 and half in the collar 6, and introduce an externally threaded pin 8 into said hole whereby said collar 6 is prevented from turning relative to said trunnion 1. 9 designates a passageway which is formed through the trunnions 4 for the admission of oil or grease to the interior of the bearing.

Mounted on the trunnion 1 and secured 110

to the trunnion 1 and secured 110

thereto is a gear wheel 10, the purpose of which will be hereinafter set forth.

The operation of the machine illustrated in the drawings is as follows:

- 5 Assume that the outer housing contains a body of water and that some of said water has passed through the apertures into the inner drum. Assume also that clothes have been placed in the inner drum and that it is desired to rotate or oscillate said inner drum to wash said clothes. Rotary or oscillatory motion will be applied to the gear wheel 10 in any suitable manner and because said gear wheel is mounted on the trunnion 1 said trunnion will be rotated or oscillated about the stationary trunnion 4 whereby the inner drum C, which is secured to said trunnion, will be actuated. When the machine is in operation the water is violently agitated, but even if some of said water finds its way through the openings in the side walls of the outer housing B through which the trunnions 1 extend, said water cannot work into the interior of the bearings as to do this it would be necessary for said water to travel over the hub of the gear wheel 10. It is also plain that it is impossible for the oil or grease from the bearing to work its way into the inner drum C.
- 10 To eliminate the opportunity for even a slight amount of water to find its way through the openings in the side walls of the outer housing B, I employ semi-circular water sheds 11, one of which is secured to the inside face of each of said side walls of said outer housing in such position that it partially surrounds the trunnion 1 which extends through the opening in said side wall. The sheds 11 are trough-shaped in cross section (Fig. I), and are intended to catch most of the water which may be

- 20
- 25
- 30
- 35
- 40

splashed about in close proximity to the openings mentioned.

While I have described my improved bearings as being a part of a clothes washing machine, it is to be understood that said bearings may be used with machines for performing many other duties, such, for instance, as fur washing and dyeing machines, and machines for chemically washing various articles.

I claim:

1. A bearing, for a machine having a stationary outer housing and a movable inner receptacle, comprising a member secured to said inner receptacle and extended outwardly through a wall of said outer housing, a supporting member secured to said outer housing, and an inwardly projecting member on said supporting member, said member on said inner receptacle being provided with a recess into which said second mentioned member extends whereby said inner receptacle is supported, and all portions of said outwardly extended member secured to said inner receptacle being located outside of said inwardly extended member on said supporting member.
2. A bearing, for a machine having a stationary outer housing and a movable inner receptacle, comprising a trunnion secured to said inner receptacle and extending through a wall of said outer housing, a spider secured to said outer housing, and an inwardly projecting trunnion on said spider, said first mentioned trunnion being provided with a recess into which said second mentioned trunnion extends whereby said inner receptacle is supported.

In testimony that I claim the foregoing I hereunto affix my signature.

ROBERT P. DUNN.
